UNITED STATES PATENT OFFICE

2,564,275

AWNNG OF METAL OR SIMILAR MATERIAL

Charles M. Préaus and Charles E. Ross,
Tulsa, Okla.

Application November 16, 1945, Serial No. 629,178

5 Claims. (Cl. 20—57.5)

1

This invention relates to awnings of metal or similar rigid material, such as solidified plastics, or a combination of such rigid materials, in contradistinction to awnings made mainly of textiles and metal frame members.

The principal object of the invention is to provide such awnings which are sturdy, comparatively light in weight, easily erected and dismembered, and inexpensive to manufacture. Such is in part accomplished by making the major portion of the roof and side panels of slats, uniform cross section, so that long strips of slat material may be stocked, from which appropriate lengths may be cut preparatory to making an awning of the desired size, thus avoiding the stocking of various sizes of roof and side panel parts, as has been the practice in the past, to suit a variety of specifications for various window sizes.

Another object of the invention is to provide such awnings embodying slatted side panels which are constructed and arranged to resist wind forces, shed moisture, and assist in bracing the roofs of the awnings, in a manner similar to the placing of sheathing in balloon framing of buildings, thus avoiding the use of solid, perforated or louvered side panels of sheet metal for rigidity.

A further object of the invention is to provide awning frames which may be made from rolled metal or molded plastic bars of angular cross section, again avoiding the necessity of stocking of various sizes and shapes of bars to suit a variety of specifications for windows of various sizes.

A still further object of the invention is to provide awnings, each made generally of three sections, such as a roof section and end panel sections, which may be compactly stored and packaged for shipment and easily handled and assembled by workman at the job to provide a sturdy awning.

Other objects and advantages of the invention will appear in the following detailed description of the preferred embodiment of our invention, taken in connection with the accompanying drawings, forming a part of this specification, and in which drawings:

Fig. 1 is a front elevational of the awning.

Fig. 2 is a side elevation thereof.

Fig. 3 is a perspective view of the awning frame, certain parts being broken away and shown in section to disclose preferred details.

Fig. 4 is an enlarged sectional view on the line 4—4 of Fig. 3.

Fig. 5 is a similar view on the line 5—5 of Fig. 3.

2

Fig. 6 is a vertical sectional view thru a roof panel of the awning.

Fig. 7 is an inner side elevation of a side panel of the awning.

5 Figs. 8 and 9 are enlarged sectional views on the lines 8—8 and 9—9, respectively of Fig. 1.

Fig. 10 is an enlarged sectional view on the line 10—10 of Fig. 2.

In the drawings we have shown the awning as 10 comprising a roof panel 13, side panels 14, and fastening devices 15 preferably provided to permit the panels to be made separate, to facilitate storage, shipment and handling, and to enable them to be assembled either prior to or while 15 installing the awning.

The roof panel preferably comprises spaced, 20 parallel, diagonally disposed side bars 16 of right angular cross section, as shown in Fig. 3, with a first flange 17 thereof uppermost and a second

25 flange 18 thereof depending therefrom; an upper horizontal cross bar 19 of obtuse angular cross section with a first flange 20 thereof in a vertical plane and a second flange 21 thereof in a diagonal plane parallel to the plane of bars 16;

25 a lower horizontal cross bar 22 of right angular cross section with a first flange 23 thereof also parallel to said last mentioned plane and a second flange 24 thereof depending from the first flange; a plurality of slats 25; and two side slats

30 26 paralleling the bars 16.

The side bars 16 are arranged so that the flanges 17 thereof extend laterally toward each other and so that a juncture 27 between the flanges 17 and 18 of each bar is outermost. Thus 35 the flanges 18 form finishing trims or skirts at the sides of the roof panel, as shown in Fig. 3.

We prefer to secure the end portions of flange 21 of cross bar 19 upon the upper ends of flanges 17 by spot welding 28, and the flange 20 may be 40 provided with perforations 29 for the reception of the shanks of screws or other fastening devices, not shown in the drawings, whereby the awning may be attached to the window frame.

Also, we prefer to secure the end portions of 45 flange 23 of cross bar 22 upon the lower ends of flanges 17 by spot welding 30 and to have the flange 24 abut the lower ends of flanges 18 thereby bracing the cross bar 22. If desired the roof frame comprising the bars 16, 19 and 22, may be

50 braced by one or more intermediate diagonally disposed bars 32 when the awning is of a size for rather wide windows. This bar is preferably of right angular cross section with a first flange 33 thereof uppermost and in the same plane as

55 flanges 17, and a second flange 34 depending from flange 33. This intermediate bar may have

the upper end portion of flange secured to the underside of flange 21 as by spot weld 35 and its lower end secured to the underside of flange 23 as by spot weld 36, the end of the bar 32 abutting against the flange 24 to brace the same.

It will be noted that the bars 16, 22 and 32 may all be cut from bar material of the same cross section, thus making it unnecessary to stock material of numerous cross sections from which the frame may be constructed, and if the stock is formed from sheet metal, such as aluminum, in contradistinction to casting, the upper bar 19 may be cut from the same stock as the bars 16, 22 and 32 and bent so that its flanges 20 and 21 are in the obtuse angular relation previously described.

Referring now to the slats 25 they are each made to comprise a longitudinally extending minor strip-like portion 38 and a longitudinally extending major strip-like portion 39 relatively wider than the minor portion 38, and in angular relation thereto. We have found that an angle of approximately 15° between the planes of these portions 38 and 39 is very satisfactory for the purpose subsequently set forth. These slats may be cut from stock strip material, such as aluminum, of uniform cross section to suit the specifications of the awnings for the size or sizes of windows to which they are to be applied. The slats 25 are disposed in spaced apart, overlapping relation, transversally of the side bars 16, with the ends of their minor portions 38 secured, as by spot welding 40 to and upon the side bars 16, with the major portions 39 angled away from the plane of the roof frame, as shown in Figs. 6, 8 and 9. The minor portions 38, intermediate their ends, may also be secured to any intermediate bar 32, by spot welding 42. It is also preferred to make the slats 25 of a length less than the width of the roof frame, so that the end margins 43 of the slats as shown in Figs. 1 and 3, are spaced inwardly from the junctures 21 between the first and second flanges 17 and 18, respectively of side bars 16. This tends to prevent injury to the ends of the slats while the panel or awning is being handled or erected, and to minimize likelihood of injury to persons, such as workmen or painters, moving in proximity to the erected awning, because the side bars act as bumpers or guards with respect to the slats disposed inwardly of the outer margins and upon the upper surfaces of the side bars.

In the drawings for the sake of clearness the slats are shown much thicker in proportion to their width and length, it being understood that the slats may be of very thin material, since the major and minor portions are in angular relation to one another and hence will not sag even tho they span a considerable distance between side bars of the frame or between such side bars and any intermediate bar. Also, as may be observed from Figs. 8 and 9, by arranging the slats in spaced apart, overlapping relation as described, ample ventilation is provided for, air currents may find exit from the pocket formed by the roof and sides of the awning so as to not subject the awning to strain during windy weather, and while the slats may be spaced apart so that the line of vision of a person looking thru the window or window opening may be directed between the slats, there is little likelihood of rain or snow finding its way to the pocket formed by the roof and sides of the

awning except when wind is blowing toward the awning.

The side slats 26 may each be cut from the same stock as slats 25 thus each comprising a minor portion 45 and a major portion 47 in angular relation as shown in Fig. 10. The minor portion is secured, as by spot welding 48 to the flange 18 of its side bar 16, parallel thereto. The lower end of each slat 26 may be cut away as at 49 to provide a tongue 50 formed partly of each the minor and major portions 45 and 47 to give neat appearance at the lower side of the awning.

As to the curtain-like side panels 14, each comprises an upright panel bar 51, a horizontal panel bar 52 and a plurality of slats 53. The bars 51 and 52 may be cut from the same stock as that used in producing the bars 16 and 22. The bar 51 comprises a first flange 54 and a second flange 55 in right angular relation thereto, and the bar 52 comprises a first flange 56 and a second flange 57 in right angular relation thereto. When the awning is assembled the first flanges 54 of the end panels are in the same plane as the flange 20 of upper bar 19 and are directed laterally toward each other. They may be provided with perforations 58 for a purpose similar to perforations 29. The upper end of flange 55 is beveled as at 59 to conform to the angular relationship of side bar 16 to flange 20 of upper bar 19 and may be provided with a perforation 60 aligning with a perforation 61 in the upper end of flange 18 and in the upper end of slat 26 to facilitate detachably securing the side frame to the roof frame. When the awning is assembled the flanges 56 of the end panels are directed laterally toward each other as shown in Fig. 3. The bars 51 and 52 are secured in right angular relation by spot welding 64 and the outer end of flange 57 is beveled, as at 65 and provided with a perforation 66 to align with a perforation 67 in the lower end of flange 18 and in the lower end of slat 26 for a purpose similar to perforations 60 and 61.

The slats 53 may also be cut from the same stock as slats 25 and 26, thus each comprising a minor portion 68 and a major portion 69. These slats 53 are arranged diagonally with respect to the bars 51 and 52 of each side panel 14 as shown in Figs. 2 and 7, and are secured to said bars as by spot welding 70 and 71 respectively. It will be noted that the slats 53 have 45° beveled ends 72 and 73 to conform to the juncture margins of the flanges 54 and 55 and 56 and 57 of the bars 51 and 52, respectively. and if the slats are first cut from ribbon-like stock and subsequently bent to provide the minor portion 68 and major portion 69 of each, there is no waste of stock since a single diagonal cut of the stock will form the beveled ends of two slats. It will also be noted that by running the slats 26 and 53 diagonally downward and outward from the upright bars 51 rain, or products of condensation gathering thereon will flow downward away from the building to which the awning is attached.

The fastening devices 15 may each comprise an ordinary or approved bolt 74 and nut 75. It is preferred to use a bolt having a wide, flat head 76, to engage the minor portion of slat 26, the shank 77 of the bolt passing thru the perforations 59 and 61 or 64 and 67, as the case may be. The side panels 14 are preferably assembled with respect to the roof panel by having the outer faces of flanges 51 and 52 of each side panel confront and

abut against the inner face of flange 18 of its respective side of the roof panel, with the slat 26 overlapping the uppermost slat 53 of the side panel, as shown in Figs. 2 and 10.

When erecting an awning the side panels may first be secured to the roof panel and the awning secured in place as a unit, or either the roof panel, or the side panels may first be placed with subsequent securing of the remainder to the building and together by use of the fastening devices 15.

When the awning is in use, any weight upon the roof portion, such as snow or ice will not distort the same since sagging is resisted by the frame and the diagonal slats 53. Likewise any wind forces entering from beneath the awning tending to lift same are resisted by the frame and the comparatively stiff slats 53.

The awning may be made comparatively light in weight so as to not subject the window frame to undue loads or forces, yet sturdy enough to withstand wind forces, and snow and ice loads in climates having severe winters.

We claim:

1. An awning of the class described, comprising an inclined roof panel having a diagonally extending angular side frame element at each side of the roof panel, each element having a depending portion provided with a slat permanently secured along the outer side thereof and extending downwardly and outwardly therefrom, side panels each including a vertical bar, a horizontal bar connected to the lower end portion of the vertical bar, and covering elements secured to said bars extending from said connection of the bars to points adjacent to their remote ends; and means securing said remote ends of said bars to the inner sides of the depending portions of the diagonally extending angular frame elements of the roof panel at each side thereof, and each slat overlapping the upper border of the covering elements of its respective side panel.

2. An awning of the class described, comprising an inclined roof panel, and side panels below the diagonal side margins of said roof panel, each side panel including a plurality of slats paralleling each other and parallel to the diagonal margin of its respective side of the roof and said slats angled outwardly and downwardly with the lower edge portion of each successive slat overlapping and laterally spaced from the upper edge portion of the next adjacent lower slat.

3. An awning of the class described, comprising a frame including spaced, parallel, diagonally disposed side bars, and upper and lower cross bars connected at ends to form a roof frame portion and upright and horizontal panel bars at each side of and directly connected to, and extending below said roof frame portion to form triangular panel frame portions rigid with said roof frame portion, said upper bar and said upright panel bars constructed and arranged for attachment to a window frame; roof slats secured to and extending transversally of said side bars; and panel slats secured to and extending diagonally between the upright and horizontal bars of each panel frame, said panel slats extending parallel to said diagonally disposed side bars of the roof frame portion and angled outwardly and downwardly with the lower edge portion of each successive slat overlapping and laterally spaced from the upper edge portion of the next adjacent lower slat.

4. In an awning of the class described, the combination of an inclined roof panel comprising an upper horizontal cross bar, a lower horizontal

cross bar, a pair of diagonally disposed side bars connected to the end portions of said cross bars, slats extending between the side bars secured at their ends to the upper sides thereof with the lower edge portion of each successive slat overlapping and spaced above the upper edge portion of the next adjacent lower slat, and a slat secured along and depending from the outer side of each of said side bars; a substantially triangular shaped side panel at each side of said roof panel, each side panel comprising an upright bar, a horizontal bar in angular relation to said upright bar with the lower and inner end portions of the bars respectively connected with each other, and a plurality of slats extending diagonally between said upright and horizontal bars of the side panel and secured to the outer sides of said bars with the lower edge portion of each successive slat overlapping and laterally spaced from the upper edge portion of the next adjacent lower slat; and fastening devices securing the upper end portions of said upright bars and the outer end portions of the horizontal bars of the side panels to the end portions of said side bars of the roof panel with the uppermost slats of the side panels behind and inwardly of said slats on the outer sides of the side bars of the roof panel.

5. In an awning of the class described, the combination of an inclined roof panel comprising an upper horizontal cross bar, a lower horizontal cross bar, a pair of diagonally disposed side bars joined to the end portions of said cross bars, slats extending between the side bars secured at their ends to the upper sides thereof with the lower edge portion of each successive slat overlapping and spaced above the upper edge portion of the next adjacent lower slat, and a slat secured along and depending from the outer side of each of said side bars, said side bars each provided with an upper transverse perforation adjacent its juncture with the upper cross bar, and a lower transverse perforation adjacent the juncture with said lower cross bar; a substantially triangular shaped side panel at each side of said roof panel, each side panel comprising, an upright bar, a horizontal bar in angular relation to said upright bar with the lower and inner end portions of the bars respectively connected with each other, and a plurality of slats extending diagonally between said upright and horizontal bars of the side panel and secured to the outer sides of said bars with the lower edge portion of each successive slat overlapping and laterally spaced from the upper edge portion of the next adjacent lower slat, said upright bar provided with a transverse perforation at its upper end portion aligned with the adjacent upper perforation of the roof panel side bar and said horizontal bar provided with a transverse perforation at its free end portion aligned with the adjacent lower perforation of the roof panel side bar; and detachably fastening devices extending through said aligned perforations securing the end panels behind the side bars with the lower edge of depending slat on each of the side bars overlapping and laterally spaced from the upper edge portions of the upper slats on the side frames whereby the depending slats on the sides of the roof frame will cooperate with the diagonally disposed slats on the side frames to provide complete curtain-like coverings for the sides of uniformly spaced overlapping slats.
